(57) **CLAIM**

The ornamental design for an osteotomy drill as shown and described.

DESCRIPTION

FIG. 1 is a front view of an osteotomy drill showing the new design; the rear view is a mirror image of the front view shown;

FIG. 2 is a left side view thereof;

FIG. 3 is a right side view thereof;

FIG. 4 is a top view thereof; and,

FIG. 5 is a bottom view thereof.

The broken lines shown in the drawings depict portions of the osteotomy drill that form no part of the claimed design.
